(57) **CLAIM**

The ornamental design for a vertical tillage system, substantially as shown and described.

DESCRIPTION

FIG. 1 is a perspective view of a vertical tillage system showing our new design;

FIG. 2 is a top plan view of the vertical tillage system;

FIG. 3 is a bottom plan view of the vertical tillage system;

FIG. 4 is a right side elevation view of the vertical tillage system, the left side elevation view being a mirror image of the right side elevation view being shown;

FIG. 5 is a front elevation view of the vertical tillage system; and,

FIG. 6 is a back elevation view of the vertical tillage system. The broken line showing of the attached features is included for the purpose of illustrating portions of the vertical tillage system and forms no part of the claimed design.
